UNITED STATES PATENT OFFICE.

GEORGE M. WHITIN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

HEILMAN-TYPE COTTON-COMBER.

1,131,976.

Specification of Letters Patent. Patented Mar. 16, 1915.

Application filed June 18, 1913, Serial No. 774,285. Renewed August 8, 1914. Serial No. 855,906.

To all whom it may concern:

Be it known that I, GEORGE M. WHITIN, a citizen of the United States, residing at Whitinsville, in the county of Worcester and 5 State of Massachusetts, have invented the following described Improvements in Heilmann-Type Cotton-Combers.

The improvement relates more particularly to a construction of close nip cotton comber adapted for operation with efficiency and high speed, and consists in certain features of the drawing-off mechanism and associated parts, as hereinafter made apparent and more particularly pointed out in 10 the claims.

In the drawings forming part hereof, Figure 1 is a vertical cross-section of one of the combing heads of a machine constructed according to this invention. Fig. 20 2 is a similar section taken on a plane close to the bearings of the several rolls. Fig. 3 is a top plan of parts of Figs. 1 and 2. Fig. 4 is an elevation thereof; Fig. 5 a detail; and Fig. 6 a modified form.

In Fig. 1 the reference numeral 1 marks the upper portion of one of the intermediate frame uprights which separate the several combing heads of the comber, forming the supports for the various operating 25 parts thereof. It will be understood without illustration that the comber may comprise a number of combing heads all alike and driven from a drivehead at one end of the machine, according to the usual Heilmann design. The drivehead is not herein shown inasmuch as the comber builder will readily supply the necessary mechanism for providing the motions assigned to the various parts referred to below. The uncombed lap is fed to the action of the combing elements over a lap-plate 2, the lower end only of which appears in Fig. 1. From the end of this lap-plate the lap is drawn into the bite of a pair of feeding members 30 or rolls 3 and 4, by which it is projected into the jaws of the nipper mechanism. The lower feed roll 3 is desirably a shaft roll, that is to say, it is formed on, or as a part of, a continuous shaft, common to all 35 of the combing heads and driven from the drivehead. It is journaled in adjustable bearings 5 on the uprights 1, in a position which will permit it to rotate as closely as possible to the nipper jaws. The upper 40 roll 4, which is individual to each head, is

held in place on the lower roll by means of a pair of holder arms 6. These arms are pivoted in rear of the feed rolls and put under the tension of springs, not shown but as customary for the feed roll holders of Heilmann machines. In the present case, however, the arms serve merely to locate the upper feed roll, imparting their pressure thereto only through the intervention of a presser roll 4^a which is superposed on the feed roll with its end gudgeons journaled in, in fact carried by, the ends of the arms. The arms thus exert their pressure on the presser roll and the latter transmits such pressure to the upper feed roll, for which purpose the presser roll is formed of full diameter only for a portion of its length and at the central region, whereby it bears on the central part of the roll 4, but presses the full length of the latter roll firmly and with a uniform pressure upon the lower feed roll, so that the two feed rolls will grip the cotton lap evenly from margin to margin. The part of the presser roll that bears on the upper feed roll is desirably fluted to fit such roll, while its end portions are reduced in diameter and cylindrical, as plainly shown in Fig. 3. By this construction and arrangement the upper feed roll may be made very slender with respect to the width of lap it serves, and may be so placed on the lower roll, without interference with the nipper knife, as to cause the common tangent of the two rolls to extend downwardly toward the path of the detaching segment approximating coincidence with the point of contact which the latter has upon the under side of the detaching roll, as indicated by the dot-and-dash line in Fig. 1. At the same time the feed rolls are located at a sufficient height relatively to the comb cylinder, to cause the lap to intersect the teeth of a stationary top comb as the tuft is being drawn away.

The nipper mechanism comprises a fixed lower jaw or cushion plate 7, and a movable upper jaw or nipper knife 8, the latter being carried on arms 9 and provided with the usual lip by which it deflects the projecting fringe of lap toward the rear of the cylinder. The nipper knife opens to a position above the tangent line just referred to during the detaching process, the fulcrum axis of the arms 9, being somewhere in the rear of the feed rolls, so that the said knife moves ap-

proximately edgewise from its closed to its open position and without conflicting with the upper feed roll. When it is closed upon the cushion-plate the fringe of lap is held at 5 a point slightly in rear of the vertical center line of the comb cylinder.

The top comb 10 is disposed immediately in front of the nipper knife but spaced from it a distance sufficient to determine the appropriate length of the fringe that is to be held in engagement with the cylinder. It is 10 preferably so set as to work in a fixed position, about as indicated in the drawings, but it is intended also to be adjustable, by means 15 not shown, to vary the depth to which its teeth may penetrate the tuft. The comb cylinder 11 comprises a combing half-lap 12, and a detaching half-lap or segment 13, carried on the main comb shaft 14, which 20 latter shaft is common to all of the heads of the comb and journaled on each of the uprights 1 thereof. The cylinder and top comb, as well as the nipper mechanism and other parts not herein specifically shown or 25 described, may be constructed, if desired, to operate in the manner shown in Patent No. 822479 dated June 5th, 1906.

Immediately in front of the top comb and as close thereto as operating clearance 30 permits, is mounted the detaching roll 15, which is preferably supported in a substantially fixed position, under the incline of the top comb and following the principles explained in the patent referred to; that is to 35 say, it is held by its gudgeons on fixed bearings which will permit it to engage the detaching segment 13 but escape the needle half-lap, the latter being set about $\frac{1}{32}$ of an inch lower on the cylinder than the segment. The detaching roll, however, may be 40 otherwise carried, as will be apparent from the further explanation of the invention.

Directly in front of the detaching roll there is mounted a pair of piecing rolls 16 and 17, in contact with each other and out 45 of contact with the detaching roll. These rolls are so placed as to take the detached tuft from the segment, turning it upwardly and passing it between themselves and 50 thence forwardly under the clearer roll 18. One or the other, preferably the roll 17, is a shaft roll common to all the combing heads and driven from the drive-head, receiving from the latter the usual 55 intermittent or alternating forward and back motion, which will cause it and the other rolls to overlap or piece the successive detachments and form them into a continuous lap emerging from between the rolls 17 and 60 18. From this point the continuous lap may be handled the same as in the ordinary Heilman comb, that is, passed through a pan-conductor and condenser, through a draw-box and coiler, into a silver-can. 65 These parts are not necessary to describe,

as they form no part of the present invention.

While the detaching roll 15 and the piecing roll 16, are out of contact with each other and also independent in their action on the staple, they are nevertheless both subject to pressure from a single roll 19, which 70 is rested in the crotch formed between them and subject to heavy pressure from a pair of stirrups 20 applied to its gudgeons or end portions. The pressure of this roll is exerted downwardly or toward the cylinder and thus urges the detaching roll toward the segment in a rearwardly direction and the piecing roll toward its mate and driver 75 17 in a forward direction. Thereby the alternating or intermittent piecing motion of the roll 17 becomes imparted to the detaching roll through the presser roll, insuring that the detaching roll will attain 80 the surface speed of the segment by the time the latter encounters it and thus also guarding against relative slipping between these parts, which is apt to take place at high speeds and is most undesirable. In 85 order that the driving effect just referred to 90 shall be positive in its action, it is preferred to flute the roll 16 as indicated, and also the presser roll 19. This, however, is not essential, and the roll 16, for instance, can be a 95 leather covered roll if the pressure applied thereto is sufficient. It is within the invention, moreover, to depress the axis of the roll 16, when it is a leather-covered roll, so that it also will be encountered by the segment like the detaching roll. This arrangement is shown as a modified form in Fig. 6 and will not require further description. When the presser roll 19 is smooth or leather-covered, which is also within the invention, the advantage is thereby gained 100 that the detaching roll will be free from the danger of indentation by the flutes and less care will then be required in removing the stirrup pressure when the machine is idle. 110

By any of the foregoing arrangements it will be observed that the detaching roll 15 may be of small diameter by which is meant considerably less than the usual $\frac{5}{8}$ inch diameter roll used in combers designed to accommodate a 12 inch lap. The superposed and relatively rigid presser roll 19 has two principal functions. It prevents the bending of the small diameter detaching roll under impact of the segment, and also assists in its rotation when it is engaged with the segment, the latter function being of course independent of the diameter of the detaching roll and hence useful even where that roll is stiff enough of itself to resist 115 flexure. The distance from the feed rolls to the bite of the detaching roll controls the length of the staple that can be efficiently combed, and in general also controls the amount of waste produced. The shorter 120 125 130

5 this distance, the less waste, other conditions being favorable, and obviously the small-diameter detaching roll enables the bite line on the segment to occur farther back than with a detaching roll of larger diameter, say as large as necessary to resist in itself the tendency to distortion or flexure. The 10 detaching roll used in this machine when supplied with the presser roll as indicated may be $\frac{5}{8}$ inch or less in diameter, and take a standard 12 inch lap. Its bite on the segment may thus be less than $\frac{5}{8}$ inch from the top comb teeth, which thus gives it an opportunity to nip the cylinder combed fibers 15 well toward their middle so as to draw through the top comb fibers of such shortness as would otherwise be thrown down as waste. I have found also that the same conditions make for less waste and more efficient 20 combing when the longer stapled fiber is under treatment, the close nip being advantageous with all grades of cotton as a means of combing and hence saving the shorter fibers.

25 It will be understood that the figures of the drawings are not strictly proportional to the actual machine but it will be evident from the relative arrangement shown that the distance from the feed rolls to the top 30 comb may be equal to or less than one inch, that is to say, not materially longer than the shortest staple that would be sought to be combed, and that the distance from the comb teeth to the bite of the detaching roll 35 may be approximately one-half of the length of such staple. Thus it will be seen that practically all of the fibers will either be held by the feed rolls or carried off by the detaching roll, very little being removed by 40 either the top comb or the rotary comb, the functions of which are primarily to remove dirt and neps and give the fiber the desired luster.

45 The supporting means for the several rolls above described are formed on the pillow block 21 of the piecing roll shaft 17, which block carries a laterally and rearwardly extending arm 22, provided with a shelf or lip 23 at its rear terminal. On 50 this shelf there is mounted first the bearing block 24 (Fig. 2) for the second or piecing roll 16, the said block being rested thereon against a set screw 25 by which the elevation of the roll 16 with relation to the detaching 55 segment can be controlled. The gudgeon of the said roll is furnished with a journal sleeve 16^a, slabbed on one side, by which it rests on the top surface of the bearing block, the said top surface being inclined 60 toward the lower piecing roll, as shown, so as to permit the roll 16 to bear upon the latter under the effect of the pressure. A suitable collar on the end of the gudgeon sleeve 16^a engages the inner edge of the bearing 65 block to prevent longitudinal motion of the

roll, for obvious reasons. The bearing block 26, shown in detail in Fig. 5, supports the detaching roll 15 and is also rested upon the same shelf 23, against the set screw 27 and against the side of the block 24 with which 70 it interlocks by means of its ribs 26^a. The latter keeps the blocks in accurate registry. A common tightening bolt 28, passing through both blocks and tapped into the arm 22, serves to secure the blocks in their 75 adjusted positions. The detaching roll gudgeons are held rotatably in gudgeon sleeves 15^a which latter are seated in the semi-circular seats 26^b in the bearing block and also are provided with collars to prevent 80 endwise shifting of the detaching roll when in action. The end of the block 26 is formed with an upstanding stop member or abutment wall 29, which keeps the presser roll from shifting longitudinally. When 85 the said presser roll is in place, bearing on the two rolls 15 and 16, the stirrups 20 are applied to its sleeves 19^a, as indicated in the figures, and the other ends of the stirrups are hooked to the weighted levers 30 90 so as to be pulled downwardly thereby. The pressure thus exerted on the detaching roll tends to urge it toward the rear side of the comb cylinder, as above stated, and which direction is best suited to eliminate 95 shock in the roll, inasmuch as the said roll can thereby yield, if need be, in the direction in which the segment is moving at the moment of contact. The pressure from the same stirrups also acts on the rearward piecing 100 roll so that both rolls 15 and 16 are thus pressed against the tufts passing beneath them, by a common pressure means.

105 The clearer roll 18 is carried in horse-tails 31 and the latter are mounted on the usual horse-tail bases 32, which are likewise carried on the pillow blocks 21 extending laterally and rearwardly therefrom, so as to embrace the stirrups, as shown in Figs. 3 and 4. A clearer cover, not shown, may be 110 applied to the clearer roll as well as to the weighting roll, for the usual purpose, such cover being held in place by the slots shown in the horse-tails.

115 I claim:

1. In a cotton comber, lap feeding and nipping means, a comb cylinder, a detaching roll and a pair of piecing rolls, in combination with a presser roll applied jointly to said detaching roll and one of the piecing 120 rolls and serving to press both against detached tufts passing beneath them.

2. In a cotton comber, the combination of a comb cylinder having a detaching segment, a detaching roll adapted to engage the segment, a second roll in front of the detaching roll, and a presser roller applied jointly to said rolls, serving to press them both upon the tufts passing beneath them.

3. In a cotton comber, the combination of 125

- a comb cylinder having a detaching segment, of a segment-engaging detaching roll, a second roll in front of this detaching roll and out of contact therewith, a third roll in front of the second and in contact therewith and a presser roller applied jointly to said detaching and second rolls adapted to press the latter toward the segment and the other toward the third, said second and third rolls being piecing rolls adapted to piece the detached tufts.
4. In a Heilman type comber, a comb cylinder, a detaching roll guided in end bearings and a pair of piecing rolls, in combination with a presser roll applied jointly to said detaching roll and one of the piecing rolls, and means for applying pressure to the ends of the presser roll.
5. In a Heilman type comber, a comb cylinder having a detaching segment, a detaching roll, a pair of piecing rolls in front of the detaching roll, and a presser roller applied jointly to said detaching roll and to one of the piecing rolls and serving to press the one toward the segment and the other toward the third piecing roll, in combination with stirrups applied to the ends of the presser roll and means for preventing longitudinal displacement thereof.
6. In a Heilman type comber, the combination of a comb cylinder having a detaching segment, of a segment-engaging detaching roll, a second roll in front of this detaching roll and spaced therefrom and from the segment, a third roll in front of the second and in contact therewith and a presser roller applied jointly to said detaching and second rolls adapted to press the latter toward the segment.
7. In a Heilman type comber, a comb cylinder having a detaching segment, a segment-engaged detaching roll, means independent of the segment for rotating the detaching roll comprising a main fluted piecing roll, a second piecing roll also fluted and driven thereby and a superposed roll driven by the said second roll.
8. In a Heilman type comber, the combination of detaching and piecing rolls out of contact with each other, a presser roll in contact with both and means for preventing endwise shifting of the presser roll.
9. In a Heilman type comber, a detaching roll, means to support the same comprising bearing blocks at the ends of the roll having upstanding parts or surfaces, a second roll in front of said detaching roll, and a presser roll bearing on both said rolls and confined in places by said upstanding surfaces.
10. In a Heilman type comber, the combination of feeding and nipping means, a detaching roll adapted to operate close in front of said nipping means, a second roll operating in front of this detaching roll, and pressure means common to both said

rolls adapted to press the same against the tufts passing beneath them.

11. In a Heilman type cotton comber, the combination of a comb cylinder having a detaching segment, a pair of nipper jaws, a pair of feed rolls in rear of such jaws, the upper roll of which is of smaller diameter than the lower roll and held on the forward side of said lower roll, in combination with a detaching roll operating on the segment, a second roll in front of the detaching roll and means common to both rolls for applying nipping pressure thereto. 70

12. In a Heilman type comber, the combination of feeding and nipping means, a detaching roll in front of the same, a second roll in front of this detaching roll, pressure applying means acting jointly on both rolls, and supporting means for the ends of such rolls whereby the detaching roll may yield under the pressure in a forward and upward direction. 80

13. In a Heilman type comber, nipper members, a comb cylinder having a detaching segment, a segment-engaged detaching roll operating close in front of the segment, a second roll in front of such detaching roll, and a third roll in front of and engaging said second roll, in combination with yielding means common to both said detaching and second rolls adapted to press them both against the tufts, and inclined end-supporting means for said detaching roll permitting the same to move forwardly and upwardly under impact with the segment. 90

14. In a Heilman type comber, the combination with a comb cylinder having a detaching segment, of a pair of feed rolls, the uppermost of which is of relatively small diameter held on the forward side of the lower roll whereby the common tangent of the said rolls substantially coincides with the path of the tuft during detachment, a pair of nipper jaws, the active jaw thereof being inclined and substantially parallel with the plane of the axes of said feed rolls, an inclined top comb in front of such active jaw, a segment-engaged detaching roll rotating under the incline of said top comb, supporting means for the ends of said roll on which it may yield forwardly under impact by the segment, piecing rolls in front of the detaching roll, and a common means for applying nipping pressure to both the detaching rolls and said piecing rolls. 105

15. In a cotton comber of the kind described the combination of a comb cylinder having a detaching segment, means for feeding and holding the forward end of the cotton lap in contact with said cylinder, a detaching roll adapted to be driven by contact with the detaching segment, a pair of rolls spaced forwardly of the detaching roll and adapted to receive the tufts from the segment, and means for transmitting the mo- 115

tion of one of said rolls to said detaching roll whereby the latter is driven coincidently by one of said forwardly spaced rolls as well as by the segment.

- 5 16. In a cotton comber, a comb cylinder having a segment, feed rolls above the same having a common tangent extending downwardly toward the cylinder, lap-nipping means comprising a nipper-knife inclined 15 in the same direction as the feed rolls, a top comb also inclined in the same direction and a detaching roll coöoperating with the segment in front of the top comb, in combination with means for supporting such roll

comprising a slotted bearing block engaging 15 an end thereof, said slot being downwardly and rearwardly inclined, and open at its upper end, piecing mechanism independent of the detaching roll and including a weighted roll, and weighting means common to this 20 roll and the detaching roll.

In testimony whereof, I have signed this specification in the presence of two witnesses.
